WINDOW OR THE LIKE

Frank Muik, Chicago, Ill., assignor of one-half
to Frank G. Watra, Chicago, Ill.

Application March 7, 1934, Serial No. 714,368

7 Claims. (Cl. 20—50)

This invention relates to windows or the like, more particularly of the type in which the sashes are mounted to move up and down in a frame and also to be swung inwardly when desired.

5 An object of the invention is to provide an improved construction whereby the sash will not only move up and down readily, but will also swing on a vertical axis whereby it may be brought into position for cleaning of the outer 10 surface of the sash, and with these features, provide an improved weather-proof construction.

My improved construction permits both the upper and lower sash to be swung inwardly in the same plane and with the upper sash more 15 nearly parallel with the lower sash than has heretofore been possible with windows of this type.

20 A further object of the invention is to provide improved means for automatically anchoring the sliding member adjacent the free edge of the sash when the sash is swung inwardly, and the novel combination with this anchoring means of a burglar lock, preventing, in desired positions, raising of the sash.

25 A still further object is to provide improved locking means preventing, when desired, the swinging of the sashes on their vertical axes.

An important feature in the invention is to 30 accomplish these results by simple metal fittings which are strong and durable, of low cost, and easily operable.

Other objects and advantages will be apparent from the following description, taken together with the accompanying drawings in which—

35 Figure 1 is a general view showing the inner elevation of my improved window;

Figure 2 is a vertical section, somewhat diagrammatic, taken on the line 2—2 of Figure 1, showing in full lines the sash in normal position, and in dotted lines an optional position;

40 Figure 3 is a horizontal section, somewhat enlarged, taken on the line 3—3 of Figure 1;

Figure 4 is a fragmentary section similar to Figure 3 but showing the sash swung inwardly;

45 Figure 5 is a vertical section in the plane of the window taken on the line 5—5 of Figure 3;

Figure 6 is a fragmentary perspective of a section of one of the slides with the automatic anchoring bar;

50 Figure 7 is a further detail of the anchoring bar, being a section taken on the line 7—7 of Figure 5, but in another position of the anchoring bar, omitting the detent plate;

55 Figure 8 is a detail of the latch lock and being a section taken on the line 8—8 of Figure 5;

Figure 9 is a fragmentary enlarged perspective of one of the sashes illustrating the latch-lock retracting plate and the anchoring bar detent; and

Figure 10 is a modified construction for old windows.

Referring in detail to the figures of the drawings, the window frame indicated as a whole by 10 may be considered to be of ordinary construction, and, for a sufficient understanding of 15 the relation of its operative parts, it will suffice to point out that it has vertical side frame members 11, 12 (Figure 3) the partition strips 13, 14, outer stops 15, 16 and inner stops 17, 18. Between these several stops and the partition strips 20 there are thus formed oppositely-disposed channels 8, 8a for one sash and 9, 9a for the other sash. What I have thus described for the frame is conventional, and the channels last-mentioned 25 are ways in which the sashes slide up and down in ordinary window construction. In this instance, however, the channels 9, 9a are closer together than the channels 8, 8a, for the purpose of the type of window construction to which this invention relates and in which the sashes 30 are pivoted on vertical axes so that they may be swung inwardly. I do not claim that this general type of construction is new, but my invention relates to improvements therein. I have marked the lower sash A and the upper sash B. 35

To adapt the window frame for my invention, I provide metallic guide members 19 which are secured in the channels 8, 8a and 9, 9a as by any suitable fastening means such as the screws 20, which desirably have their heads countersunk in 40 the face of the guides 19. These guide members have their vertical margins 21 turned in toward each other to provide telescoping engagement with the members adapted to slide on the guides 19. The guides 19 are desirably offset as at 45 centrally thereof throughout their vertical length and intermediately of the inturned margins 21 and desirably into the same plane as the inturned margins. Shoulders formed in this instance by upper margins of slots 23 are located in this offset portion of the guides, at one side of the window, spaced apart vertically throughout substantially the entire length of the guides.

Slide members 24, 24a are provided for one side of the window to slide on the guides at that side. 50 The slide members 24, 24a, in accordance with my invention, are formed of sheet metal as are the guides 19, but the slide members 24, 24a are of box or hollow formation, having their margins 55 bent around the inturned margins 21 of the 55

guides, to provide grooves receiving the guides, thus affording a telescoping sliding interlocking engagement between the slides and the guides. A metal-to-metal engagement is provided eliminating contact of any sharp edges of the metal with the wood frame of the window. It will be understood that the slides 24, 24a for each sash are of less height than the guides, and are of the same height or vertical length as their respective sash.

10 The sashes are hinged to the slides 24, 24a so that they may be swung inwardly of the room as indicated in Figures 2 and 4, and are adapted to have locking engagement with the slides 26, 26a respectively when swung into the plane of the slides.

15 The lower sash A is permanently but pivotally secured to its slide 24 by a hinge indicated generally by the numeral 27 which is desirably of the piano-bench type as best shown in Figure 1. This hinge 27 includes a leaf or leaves 28 secured to the face of the slide 24 as by rivets 29 and another leaf or leaves 30 secured to the sash A, these leaves having the usual vertically aligned and alternated cylindrical hinge lugs 31 through which pass a hinge pin 32 extending substantially the height of the sash. The leaf 30 may be secured to the sash A by screws 33 which at the same time, as here shown in Figure 3, may secure to the sash a flexible metal weather-strip 34 also extending throughout the height of the sash and having an angular portion 35 which, when the sash is in the plane of the slides, is snugly received in an exterior groove 36 formed in the face of the slide 24 as by bending a reentrant portion of the metal of the slide inwardly upon itself. The weather-strip 34 is desirably normally spaced from the sash, in this instance by the hinge leaf 30, so as to permit flexing of the strip to resiliently accommodate itself to the groove 36. The sash A is advantageously rabbeted as at 37 to provide this spacing from the weather-strip 34 and also to accommodate the hinge 27. This results also that the sash at 38 laps the angular portion 35 of the weather-strip to abut the slide 24 and further safeguard against entrance of the elements.

45 The slide 26 at the other side of the window, to which the sash A is adapted to be optionally locked, is generally similar to the slide 24 but is formed somewhat like an inverted L having a reentrant portion 39 in its base forming an exterior groove adapted to receive a weather-strip on the sash A. For this purpose the sash is rabbeted as at 40 to receive the base of the L of the slide, and the flexible metal weather-strip 41, which is also L-shaped as here shown, is secured in this rabbeted portion of the sash as by a screw 42 adjacent the upper end of the upright of the L of the weather-strip. On its base, which abuts the base of the slide, the weather-strip is advantageously bent around upon itself to form a bead 43 which is snugly received in the groove 39 of the slide. The weather-strip 41 is desirably of a flexible metal such as copper, and except where it is fastened to the sash, is spaced from the sash as at 44 so as to be permitted to flex to resiliently center and accommodate itself in the groove in the slide.

50 I have provided improved means for locking the sash to the slide 26 which as here shown includes the latch-lock indicated as a whole by the numeral 45 and shown in detail in Figure 8. In this instance, the sash is recessed to receive a latch housing 46 having a face plate 47 set back into the edge of the sash, as best shown in Figure 9, and having an aperture 48 therein to receive therethrough the latch bolt 49. The latch bolt which may have a somewhat hollow shank 50, together with the casing 46, houses a compression spring 51 which presses the latch bolt outwardly through the aperture 48 within the limits of shoulders 52 which engage the face plate 47. When the sash is swung into the plane of the slide 26 on its hinge 27 from its position, as in Figure 4 where it is shown swung inwardly into the room, the curved or inclined cam portion 53 of the latch bolt rides on the slide 26 and the latch bolt is retracted until the slide 26 and the weather-strip 41 are snugly interlocked (at which time the slide 24 and weather-strip portion 35 will also be snugly interlocked) whereupon, when the sash is also in vertical alignment with the slide, the latch bolt 49 springs into an aperture 54 in the face of the slide 26 (Figures 5 and 8) this aperture being substantially the same height vertically of the sash and slide as the latch bolt. Until the latch bolt is retracted, the sash A is thus securely locked to the slide 26 against swinging movement on its hinge 27 and also for vertical movement with the slide 26. For greater security I desirably provide two of the latch locks 45 adjacent the upper and lower corners of the sash. It will be understood that when the sash is thus locked to the slide 26, the sash A and the two slides 24, 26 move as a unit upwardly or downwardly in the channels 8, 8a, and on the guides 19 maintained in these channels in a state of equilibrium in any selective position therein by the usual sash-weights 55 which are connected by cords 56 to the slides as at 57 (Figure 5) the guides having openings 58 therein near their tops which permit the cords 56 and the usual pulley wheels 59 to turn therethrough. The screw or bolt 57a, securing the cord to the slide, desirably has its head (not shown) countersunk in the face of the slide, and a nut 57b on the bolt 57a clamps the parts together, the cord, the inner end of the bolt, and the nut being received within the open upper end of the slide 26.

55 I provide simple and novel means for retracting the latch bolts 49 of the locks 45 when it is desired to release the sash from the slide 26 and swing the sash inwardly. For this purpose I have shown a retracting plate 60 (Figure 9) pivoted as at 61 in the same recess in the edge of the sash which receives the face plate 47, to be substantially flush with the edge of the sash. The retracting plate also has an aperture 62 therein which in one position of the retracting plate registers with the aperture 48 in the face plate. By means of a finger-piece 63 on the retracting plate, accessible at the inner face of the window when the sash is in the plane of the slide, the retracting plate 60 may be swung on its pivot transversely of the sash and latch bolt so that a margin of the aperture 62 (beveled as indicated at 62a) rides across the cam surface 53 of the latch bolt and retracts the bolt from the aperture in the slide, thus permitting the swinging of the sash away from the slide. To permit this limited pivotal movement of the retracting plate 60, the plate has an arcuate slot 64 at its end opposite its pivot through which passes the small headed stud 65 on the fixed face plate 47.

60 It will be understood that when the sash is swung inwardly on its vertical axis, some means must be provided for preventing the slide 26 from rushing to the top of the window under the influence of the sash-weight 55. For this purpose I

have provided a novel anchoring bar indicated generally by the numeral 66, which acts as a weight-restrainer and also, as later pointed out, serves as a burglar lock. The anchoring bar 66 is pivoted intermediately at 67 upon the interior of the hollow slide 26, as through the intermedium of a bracket 67a suitably secured to the interior of the slide, as by the rivets 67b on the face of the slide opposite the guide 19. At its lower end the bar has a tongue 68 spring-pressed as by a torsion spring 69 toward the guide 19, adjacent thereto. At its upper end the anchoring bar 66 has an extension or button 70 thereon which may project through the slide through the hole 71 therein. When the sash is swung away from the slide 26, the spring 69 urges the lower end of the locking bar into one of the slots 23 in the guide 19 to lock the slide against vertical movement under the influence of the sash-weight, but when the sash is swung into the plane of the slide, the edge of the sash rides over the rounded face of the button 70 and by abutment with the button 70 rocks the anchoring bar at its lower end out of the slot 23 so, that when the sash and slide are thereafter in the same plane, the anchoring bar is normally ineffective, and the sash and slide, together, are permitted to be raised or lowered and to be responsive to the counter-balancing influence of the weight 55. There are times, however, when it is desirable to lock both the slide and the sash against vertical movement in selected positions vertically of the window, as for example when it is desired to leave the sash partially open vertically, for example for ventilation, but to have the sash fixed in this position to prevent further opening of the sash for unlawful entrance. For this purpose, I have shown novel means for causing the anchoring bar 66 to act also as a burglar lock. To accomplish this result the button 70 on the anchoring bar normally abuts a manually-movable detent plate 72, pivoted at 73 on the edge of the sash adjacent the button 70. The detent plate 72 has a finger-piece 74 accessible at the inner face of the window so that the detent plate may be swung out of abutment with the button 70. The edge of the sash is recessed behind the detent plate at 75, as best shown in Figure 7, to permit the button 70 to spring into this recess and the bar to rock so that tongue 68 thereof may be received in one of the slots 23 in the guide even when the sash is in the plane of the slides. As best shown in Figure 9, the detent plate 72 is conveniently carried by face plate 76 which is discontinued opposite the recess 75, and the face plate 76 and detent plate 72 are set into the edge of the sash to be substantially flush therewith, just as are the face plates 47 and retracting plate 60 of the latch locks. The anchoring bar and its operating mechanism are desirably located medially of the sash and slide and are thus identified by the user, while the latch locks 45 are located nearer the corners of the sash.

The upper sash B and its slides and guides are similar to sash A, but sash B is somewhat narrower than sash A (the channels 9, 9a being closer together than the channels 8, 8a as already mentioned) to permit sash B to be swung on its vertical axis past the parting strips 13 and the slide 26. It will be understood also that, for adaptation to old windows, where the channels 8, 8a and 9, 9a are equal distances apart, the slides for the sash B may be made wider (as 24b, in

Figure 10) to accommodate the smaller width for the sash B.

A common objection to windows of this type is that the sash B is prevented by sash A from swinging inwardly to a convenient angle, and I have provided novel means for permitting the sash B to swing to a sufficiently useful angle and more nearly parallel with the sash A when the sashes are in extreme inwardly-swung position. For this purpose I have provided a double-acting hinge for the sash B, indicated generally by the numeral 77. This hinge may include the usual leaf or leaves 78 suitably secured to the face of the slide 24a, an intermediate leaf or leaves 79 pivoted to the leaf 78 by the hinge pin 80, and another leaf or leaves 81 suitably secured to the sash B and pivoted to the intermediate leaf 79 by the hinge pin 82, the intermediate leaf 79 thus spacing the sash from the slide 24a when in its swung position as shown in Figure 4 and permitting the sash to pass somewhat around the sash A. When the sash B is swung to closed position into the plane of the slides 24a and 26a, the leaves 78, 79 and 81 fold together as shown in Figure 3 into a relatively small space, the sash B being rabbeted similarly to sash A for this and other purposes.

The sash B is provided with similar weather-strip provisions as sash A and with similar latch locks and anchoring bar, all of which need not be again described.

It will be understood that when the sashes are swung to closed position into the planes of the pairs of slides respectively, the sashes and their respective slides 26 and 26a may not at first register vertically. It is desirable, however, that the sash shall always be vertically in register or somewhat above its respective slide 26 or 26a, as the case may be, when first swung into the plane of the slide, and for this purpose I have provided a shelf 83 on the foot of the slide 26 and a similar shelf on the foot of the slide 26a so that its respective sash cannot be swung into its plane unless the sash is above this shelf. Thereafter, the sash may simply be pushed down until it rests on the shelf 83, or, as generally happens, the weight 55 will pull the slide up to locking position in register with the sash. The sash is desirably rabbeted to receive the shelf flush with the lower edge of the sash. When so received, the latch locks 45 are operative automatically, provided the retracting plates 60 are centered to have their apertures 62 in register with the apertures 48 and 54 so that the locking bolts are projected through all of these apertures. At the same time also the recess 75 is in register with the button 70 to permit the anchoring bar 66 to be operative as a burglar lock when the detent plate 72 is swung to expose the recess 75. At this time if the sash A is in its lowermost position and the anchoring bar operative, the tongue 68 will be received in the lowermost slot 23 of the fixed guide 19 and the sash will be locked in this lowermost position.

It will be further understood that when the sash is in its lowermost position, for weather-excluding purposes, it is desirably depressed below the ledge 84 of the window-frame 10, as shown in Figure 2. When it is desired to swing the sash inwardly, as already described, the sash and its slide 26 must of course be raised slightly above this ledge 84. Similarly, with the upper sash B as shown in Figure 2, it must be lowered at least slightly from its uppermost position before it can be swung inwardly, and usually the upper sash B is lowered into the same vertical plane as the

sash A before it is swung inwardly, as this places both of the sashes at a convenient height for cleaning the outer face thereof.

If desired, a filler 87 such as a block of wood or 5 the like may be shaped to the cross-section of the slides 26 and 26a and secured in the foot of the slide, as indicated in Figure 5, to stop drafts from passing through the slide.

Any suitable means may be provided for 10 weather-excluding purposes between the sashes A and B, and in this instance I have shown the sashes provided with check-rails 88 and 89 respectively, which when the sashes are in fully-closed position, meet tightly on a plane 85 (Figure 2) which is somewhat inclined to cause a 15 wedging action between the sashes, that serves to exclude weather at this point. It will be noted that my improved double-acting hinge 77 permits the sashes to be constructed with these meeting 20 check-rails, as without the double-acting hinge for the upper sash B the check-rail 89 could not be swung past the partition strip 13. The usual catch 100 may be employed to lock the sashes together.

25 While the construction I have shown and described is highly weather-proof and at the same time substantially noiseless in operation, I may make further provision for maintaining a tight water-proof and non-rattling engagement between the parts as by resilient means such as the leaf springs 86 carried on the inner faces of the slides at one or more points thereon and pressing against the guides 19 to press the parts yieldingly but firmly together and at the same time to permit 30 free sliding movement of the slides on the guides. In this instance the bowed portions of the springs 86 ride on the offset centers 22 of the guides. Also the springs 86 will provide enough friction to permit the sash-weights 55 to be eliminated, if desired, for very small windows.

Obviously, the invention is not limited to the details of construction shown for purposes of illustration. Furthermore, it is not essential that all features of the invention be used conjointly, 45 as various combinations and sub-combinations may be variously and advantageously employed.

This application is a continuation in part of applicant's pending application Serial No. 627,- 840 filed August 9, 1932, which is hereby abandoned.

Having described my invention, I claim:

1. In a window construction of the class described, the combination with a guide member fixed in each channel at each side of the sash, said 55 guide member having its vertical margins turned in upon itself and having its vertically-extending central portion offset toward the plane of said inturned margins; a box-like hollow slide member at each side of the sash having grooves receiving said inturned margins of the guide and 60 adapted to slide thereon; means for securing the sash pivotally to the slide at one side of the sash to swing into and out of the plane of the slides; a flexible metal weather-strip secured to the sash 65 adjacent each slide; a reentrant portion formed in each of the hollow slide members by bending the material of the slide member inwardly upon itself snugly receiving the weather-strips when the sash is in the plane of the slides; an inter- 70 medially-pivoted anchoring bar carried within the slide adjacent the free edge of each sash; an aperture in the slide adjacent one end of the bar receiving said end therethrough, said anchoring bar being spring-pressed at its opposite 75 end toward the adjacent guide; a tongue at the

end of the bar directed toward the adjacent guide; slots in the guide at intervals vertically thereof to receive the tongue and thereby anchor the slide against vertical movement; a recess in the sash adjacent the first-mentioned end of the bar receiving the said end to permit the spring to cause interlocking of the bar and guide when the sash is in the plane of the slides; and manually-operable means for ejecting the end of the bar from said recess against the force of the spring to permit vertical movement of the sash and slide on the guide.

2. In a window construction of the class described, the combination with a window frame having a sash, of a guide member at each side of the window; box-like hollow sheet metal slide members adapted to slide on the guides; means for hinging the sash to one of the slides on a vertical axis to swing into and out of the plane of the pair of slides; a flexible metallic weather-strip secured to the sash adjacent each slide; a reentrant portion formed in each hollow slide member by bending a face of the slide inwardly snugly receiving the weather-strip when the sash is in the plane of the slides; and means for securing the sash optionally to the other slide of the pair to fix the sash in said plane.

3. In a window construction of the class described, the combination with a sash swingable on an axis, of a guide fixed in the plane of the sash in one position thereof; slots in the guide spaced vertically thereof; a hollow slide having telescoping engagement with the guide for normal vertical movement thereon an anchoring bar pivoted intermediately within said slide, said bar having a tongue at one end directed toward the guide; a spring pressing the said tongue into engagement with the guide to be received in one of the slots to anchor the slide against vertical movement on the guide; a button at the other end of the bar; a hole in the slide receiving said button therethrough when the tongue is in one of the slots; a manually-operable detent pivoted on the sash in one position engaging the button to rock the bar to withdraw the tongue from engagement with the guide to permit movement of the slide on the guide; and a recess in the sash exposed upon movement of the detent out of engagement with the button to receive the button to permit the tongue of the bar to engage the

guide with the tongue received in one of the slots; and means for locking the sash to the slide against both vertical and swinging movement of the sash whereby both the sash and the slide are selectively locked to or unlocked from the guide.

4. In a window construction of the class described, the combination with a sash swingable on a vertical axis, of a guide fixed in the plane of the sash in one position thereof; shoulders on the guide spaced vertically thereof; a hollow slide having telescoping engagement with the guide for vertical movement thereon; an anchoring bar pivoted intermediately within said slide, said bar having a tongue at one end directed toward the guide; a spring pressing the said tongue into engagement with the guide to be engaged by one of the shoulders to anchor the slide against vertical movement on the guide; an angular extension at the other end of the bar; a hole in the slide receiving said angular extension therethrough when the tongue is in engagement with one of the shoulders; a detent pivoted on the sash in one position engaging the angular extension to rock the bar to withdraw the tongue from engagement with the guide to permit move-

- ment of the sash and slide on the guide; and a recess in the sash to receive the angular extension when disengaged from the detent to permit the tongue to engage one of the shoulders on the 5 guide; and means for locking the sash to the slide against both vertical and swinging movement of the sash whereby both the sash and the slide are selectively locked to or unlocked from the guide. 5. In a window construction of the class described, the combination with a sash and a slide, of the means for locking the sash to the slide including an aperture in the slide and a latch lock on the sash having a bolt with a cam surface thereon whereby the sash may be swung into 10 the plane of the slide and the bolt of the lock retracted by engagement of said cam surface with the slide adjacent the aperture; a spring thereafter pressing the bolt into the aperture; a 15 retracting plate pivoted to the sash for movement transversely thereto, said plate having an aperture therein normally permitting the bolt to pass freely therethrough into the aperture of the slide, a margin of the aperture of the plate being adapted to ride on the cam surface of 20 the lock bolt by pivotal movement of the plate transverse to the sash to retract the bolt from the aperture in the slide to permit swinging of the sash out of the plane of the slide. 6. In a window of the class described, the combination of a sash swingable on a vertical axis, 25 a guide fixed in the plane of the sash in one position of the sash, a slide having telescoping engagement with the guide to slide vertically thereon and lockable to the sash when the sash is in the plane of the slide and guide, a weight counterbalancing the slide and sash, means for automatically locking the slide to the guide when the sash is swung out of the plane of the slide and guide, and manually-operable means for causing said first-mentioned means to also lock the sash and slide to the guide when the sash is in the plane of the slide and guide. 7. In a construction of the class described adapted for use with a sash and frame member therefor defining a plane common to the sash and frame in one position of the sash, and provided with means for swinging the sash into and out of said plane, the combination including a recess between the sash and frame member, a spring-pressed locking element yieldingly mounted to span the space between the sash and frame member, and receivable in said recess when the sash is in the plane of the frame member, said locking element having a cam surface thereon, and a manually operable cam plate mounted to swing transversely between the sash and frame member and selectively movable to engage the cam surface of the locking element to retract said element from said recess to permit swinging of the sash out of the plane of the frame member. 80 35 90 95 100 105
